Patented Jan. 7, 1919.

UNITED STATES PATENT OFFICE.

SAMUEL S. CORNELIUS, OF MONETT, MISSOURI.

OUTDOOR FURNACE.

1,290,100.

Specification of Letters Patent.

Patented Jan. 7, 1919.

Application filed March 15, 1918. Serial No. 222,771.

To all whom it may concern:

Be it known that I, SAMUEL S. CORNELIUS, a citizen of the United States, residing at Monett, in the county of Barry and State of Missouri, have invented a new and useful Outdoor Furnace, of which the following is a specification.

The device forming the subject matter of this application is an outdoor furnace, and 10 the invention aims to provide, in combination with a furnace, a kettle having a novel means for bulging out a portion of the wall of the furnace, to provide a space between the furnace and the kettle, so that the products of combustion may escape.

It is within the province of the disclosure to improve generally and to enhance the utility of devices of that type to which the present invention appertains.

20 With the above and other objects in view which will appear as the description proceeds, the invention resides in the combination and arrangement of parts and in the details of construction hereinafter described 25 and claimed, it being understood that changes in the precise embodiment of the invention can be made within the scope of what is claimed, without departing from the spirit of the invention.

30 In the accompanying drawings:—

Figure 1 shows in top plan, a device constructed in accordance with the present invention, the lid and the stack having been removed;

35 Fig. 2 is a vertical longitudinal section wherein the lid and the stack appear as added elements; and

Fig. 3 is a fragmental section taken approximately on the line 3—3 of Fig. 2.

40 Fig. 4 is a fragmental elevation of the kettle.

In the accompanying drawings, the numeral 1 indicates a tubular furnace, which may be made out of sheet iron or any other 45 yieldable and somewhat resilient material, the furnace 1 being provided adjacent its lower end with a stoke opening 2 and having handles 25. A kettle 3 is seated in the upper end of the furnace, and is provided 50 with an inclined supplemental wall 4, the lower end of which is joined as shown at 5 to the main wall of the kettle 3. When the kettle 3 is thrust downwardly into the furnace 1, the inclined wall 4 bulges out the

furnace 1 at the back, so that, as shown at 55 17, a space exists between the main wall of the kettle 3 and the furnace 1. The upper end of the supplemental wall 4 is connected with a flange 7 on the kettle 3, the flange 7 overhanging and closing the upper 60 end of the space 17 formed between the bulged out parts 6 of the furnace and the wall of the kettle. The flange 7 is extended, at a decreased width, around the periphery of the kettle 3 and, coacting with the upper 65 end of the furnace 1, serves to uphold the kettle in the furnace. The flange 7 is supplied with a pipe collar 9 forming an outlet communicating with the space existing between the wall 4 and the main wall of the 70 kettle. On the collar 9 may be mounted a stack 10. Plates 11 extend between the supplemental wall 4 and the main wall of the kettle and serve to reinforce and strengthen the wall 4. As shown at 12, the plates 11 75 terminate at some distance above the point where the lower end of the wall 4 joins the wall of the kettle as indicated at 5.

The kettle 3 may be supplied with handles 14, and upon the kettle may be placed 80 a lid 15 having a handle 16.

In practical operation, the products of combustion generated in the furnace 1 below the kettle 3 pass upwardly through the space 17. Thence, the products of combustion pass 85 laterally into the space between the supplemental wall 4 and the main wall of the kettle, below the plates 11, and ascend, between the plates, through the collar 9 and out of the stack 10. 90

The structure hereinbefore described is of utility in that a kettle 3 of the kind herein alluded to, may simply be thrust downwardly into an ordinary tubular furnace 1, the furnace being bulged as shown at 6, so 95 as to permit the products of combustion to pass upwardly between the wall of the furnace and the main wall of the kettle, the products of combustion entering the space between the supplemental wall 4 and the 100 main wall of the kettle, and ultimately leaving by way of the collar 9 and stack 10. A person equipped with a kettle 3 of the kind mentioned, need not provide himself 105 with any specific and specially constructed furnace since, when the kettle is thrust downwardly into the furnace, the furnace, although of the ordinary tubular construc-

tion, will be so bulged that the products of combustion can escape.

Having thus described the invention, what is claimed is:—

- 5 1. In a device of the class described, a tubular furnace; and a kettle seated in the furnace, the kettle having an offset supplemental wall which bulges the furnace outwardly to permit the products of combustion to pass upwardly between the kettle and the furnace, the kettle having an outwardly extended flange whereunto the upper end of the supplemental wall is connected, the flange covering the upper end of the 10 space existing between the kettle and the bulged part of the furnace, the flange having an outlet communicating with the space between the supplemental wall and the main wall of the kettle.
- 15 2. A device of the class described, constructed as set forth in claim 1, and further characterized by the fact that upright plates extend between the supplemental wall and the main wall of the kettle, the lower end 20 of the supplemental wall being joined to the main wall of the kettle, and the plates ter-

minating in spaced relation to the point of juncture between the supplemental wall and the main wall.

3. In a device of the class described, a 30 tubular furnace; and a kettle seated in the furnace, the kettle having an outwardly extended supplemental wall which bulges the furnace outwardly to permit the products of combustion to pass upwardly between the 35 side of the kettle and the bulged part of the furnace, the kettle having an outwardly extended flange covering the upper portion of the space existing between the side of the kettle and the bulged part of the furnace, 40 the flange having an outlet communicating with said space, there being an upright plate at the upper end of said space, the plate being connected to the flange and to the side of the kettle.

In testimony that I claim the foregoing as my own, I have hereto affixed my signature in the presence of two witnesses.

SAMUEL S. CORNELIUS.
